(57) **CLAIM**

The ornamental design for a dual indicator light pregnancy testing device, as shown and described.

DESCRIPTION

FIG. 1 shows a perspective view of a dual indicator light pregnancy testing device;

FIG. 2 shows a front view of the dual indicator light pregnancy testing device;

FIG. 3 shows a rear view of the dual indicator light pregnancy testing device;

FIG. 4 shows a right side view of the dual indicator light pregnancy testing device;

FIG. 5 shows a left side view of the dual indicator light pregnancy testing device;

FIG. 6 shows a top plan view of the dual indicator light pregnancy testing device; and,

FIG. 7 shows a bottom plan view of the dual indicator light pregnancy testing device.

The broken lines depict portions of the dual indicator light pregnancy testing device that form no part of the claimed design.
